UNITED STATES PATENT OFFICE.

JOHN M. MARLIN, OF NEW HAVEN, CONNECTICUT.

MAGAZINE-GUN.

SPECIFICATION forming part of Letters Patent No. 334,535, dated January 19, 1886.

Application filed November 15, 1884. Serial No. 147,994. (No model.)

To all whom it may concern:

Be it known that I, JOHN M. MARLIN, of New Haven, in the county of New Haven and State of Connecticut, have invented a new and useful Improvement in Magazine - Guns, of which the following is a specification.

My invention relates to magazine fire-arms; and it consists in certain improvements in the parts thereof which transfer the cartridge from the magazine to the barrel, substantially as hereinafter described and claimed.

In the drawings, Figure 1 represents the breech and rear part of the barrel of a magazine-gun, partly in section. Fig. 2 represents a portion of Fig. 1, including the point of junction of the carrier and magazine, with the carrier in section. Fig. 3 is a side view of the carrier, showing one side of it. Fig. 4 is a view of the same on the opposite side. Fig. 5 is a top view of the same. Fig. 6 is a front end view of the same. Fig. 7 is a rear end view of the same. Fig. 8 is a view of the same in vertical longitudinal section. Fig. 9 is a separate view of a stop or spring to be attached to the carrier.

A is the breech of the gun.

B is the barrel.

M is the magazine-tube.

F is a frame-work of metal connecting the barrel and magazine, and constructed to receive and carry the mechanism of the carrier, breech-bolt, and lock mechanism.

C is the carrier, which slides vertically up and down in a slot or mortise extending vertically through the frame F, as shown, and immediately in rear of the magazine and barrel. The magazine-tube M is intended to receive and hold another removable tube constituting the magazine proper, and having a bore of the same diameter as the passage m. The magazine-tube M may, however, be used directly for the magazine by reducing its internal bore to the size of the passage m. The cartridges are fed through this passage and into the carrier, in the usual manner, by the pressure of a spring upon the cartridge nearest the left-hand end of the magazine in the position of Fig. 1. The carrier C is raised and lowered by the lever e, which is moved up and down by the lever N, the latter being pivoted at n, and at its lower end forming the trigger-guard of the arm,

while its upper end projects into the slot n' in the breech-block n'', and withdraws it at the same time that the carrier C is raised. The lever e projects into a slot, c, in the carrier, and has a lug or projection on the upper or right-hand side of lever N, and extending across the path of the latter, and another on the lower side of lever N in like position. As the lever N is swung up or down, it strikes against these lugs and raises and lowers lever e, the latter being pivoted at s'. The carrier C has a chamber, c', bored longitudinally through it, to receive the cartridge in the ordinary manner, and a slot, c'', reaches from the upper side of the carrier downward to this chamber. When the carrier is lowered, as described, the chamber c' comes opposite the passage m into the magazine, and when it is raised the chamber comes opposite the bore of the barrel. When opposite the magazine, the pressure of the spring in it against the series of cartridges at one end forces the cartridge at the other end into this chamber c' of the carrier, and when opposite the bore of the barrel the forward end of the breech-block n'', which is shaped properly for the purpose, passes through this chamber c' and forces the cartridge into the breech of the barrel. The carrier then descends to receive the next cartridge from the magazine, the slot c'' allowing the part n'' of the breech-block to pass through it and this movement to occur. It will be readily understood that the proportions of the levers e and N, and position and proportions of the slots in the breech-block and carrier in which they work, are such as to produce these movements of the breech-block and carrier, as described.

Heretofore it has been customary to provide a fixed stop in the chamber c' of the carrier far enough back from the open end of it, which abuts against the magazine-passage m, to just allow a cartridge to be received in it and have the end of the cartridge just come even with this abutting end of the chamber. This was necessary, because if the end of the received cartridge projected beyond the chamber it would be jammed against the frame as the carrier was raised up, while if it did not come out as far as this abutting end of the chamber c' the next cartridge in the maga-

zine would partly enter the chamber c^2 and prevent its being raised to the barrel. As the cartridges vary slightly in length, however, even the method of placing the stop in the carrier does not prevent the jamming of it in one way or the other to some extent in practical use. To avoid this difficulty, I form the carrier with a slot, c^4 , in the end face of it, which runs against the barrel and magazine, this slot being narrower than the diameter of the cartridge-head transversely, but slightly broader than the cylindrical part of the cartridge. I then undercut this slot laterally, so as to leave lips c^5 on each side at its outer edge, the under-cut being of sufficient transverse breadth to allow a cartridge-head to slip easily through up and down behind the lips. I next cut off or terminate the lips c^5 at their bottom ends, so as to allow a cartridge-head to just pass by them and rest in the bottom of slot c^4 at the time when the carrier is raised, so as to bring the chamber c^2 opposite the bore of the barrel.

Opposite the chamber c^2 , on the outside of the carrier, I make a longitudinal groove in its face and carry it around the front end of the carrier into the chamber c^2 , and in this groove I fix the spring o by the screw o' , this spring having a right-angled hook-shaped end, o^2 , that extends around the end of the carrier in the slot and projects in line with one of the lips c^5 , before described. This right-angled end of the spring, that projects across the front end of chamber c^2 , has its outer face flat and substantially parallel and coinciding with the front face end of the carrier; but the inner face of this projecting end of the spring o in the chamber c^2 is beveled off, as shown. This spring will therefore prevent a cartridge from being shoved head end foremost into chamber c^2 from the front end face of the carrier; but when a cartridge already in the chamber is forced ball end foremost out of its front end the bevel on the inside of the end of the spring o will cause it to yield and allow the cartridge to pass out.

The operation of this part of the device is as follows: When the carrier C is raised, with its chamber c^2 opposite the bore of the barrel, the lips c^5 will be carried upward far enough to allow the head of a cartridge in the magazine to pass by them and rest against the bottom of slot c^4 . As the carrier is lowered to bring chamber c^2 opposite the magazine, the head of the cartridge will pass behind lips c^5 and the projecting end of spring o until, when the chamber c^2 comes opposite the magazine, this cartridge will be pressed into the chamber in the usual manner. When the head of the following cartridge, which is pressing upon the first, reaches the bent end of the spring o , its progress will be arrested, and it cannot enter the chamber c^2 until it has first passed behind the lips c^5 , as before described, after the carrier is raised to bring the first cartridge in line with the barrel. The second or following car-

tridge can never jam the carrier owing to the first or preceding one being too short, nor can the first or preceding cartridge jam the carrier because too long, because I place my stop in the chamber c^2 far enough back from the front end to allow the longest cartridge to pass entirely within the chamber. I am enabled to do this, since I no longer depend on this stop to arrest the second or following cartridge at the right place in the magazine.

In order to present a smooth and even passage-way for the cartridges to slide over into the carrier, as well as to insure the head of the shell passing smoothly behind the lips c^5 as the carrier descends, I attach a tongue, u , to the rear side of the frame-work, below and behind the magazine-tube M , as shown in Fig. 1 in dotted lines and in Fig. 2. This tongue fits and fills the slot c^4 in the carrier, so as to slide freely therein, and it has a rearwardly-projecting lip on its lower end, that fits into a corresponding cavity, u' , in the carrier C when the latter has reached its lowest point of descent, and thus arrests its motion at exactly the right point.

On one side of the carrier C , I attach a spring, v , by a screw, v' , and form the free end of the spring in two branches, as shown in Fig. 3. Underneath each of these branches a small transverse hole, v^2 , is bored through the wall of the carrier into the chamber c^2 . A plunger, v^3 , is made long enough to reach into chamber c^2 , with a head like a common screw, the groove across the face of the head being wide enough to receive either member of the bifurcated end of spring v . By inserting the plunger v^3 into one of the holes v^2 it can be turned so as to have a member of this end of spring v , which also turns on screw v' , drop into the groove across the head, and this will hold it securely in place, and its inner end, projecting into chamber c^2 , thus forms a stop for the cartridge in the chamber.

By the use of any sharp-pointed tool the spring v can be lifted and the plunger v^3 transferred to the hole under the other member of the bifurcated end of spring v very easily and quickly, to adapt it to a different length of cartridge.

It is obvious that the spring o and groove c^4 could be made effective to operate in the manner before described, even if the lips c^5 were dispensed with and the groove c^4 made of the same width as at the bottom its entire depth, because only one cartridge could enter the chamber c^2 at a time; but I prefer to use the lips, as in case the carrier was accidentally moved slightly upward, so as to allow the following cartridge-head to enter the slot c^4 , and then brought down again, there would be some liability of the head of such following cartridge coming into contact with the ball end of the one already in the chamber c^2 . If the back-stop plunger v^3 be, however, placed far enough from the delivery end of chamber c^2 , the cartridge in the chamber could, however,

yield enough to pass by the head of the following one, even in the case last supposed.

I do not in this application claim any improvement herein shown in the breech-bolt, 5 lock, firing, or extracting mechanism, as I propose to make such improvement the subject of another application for Letters Patent which I propose to make therefor; neither do I claim the lips c^5 c^6 in any other combination with the carrier-block than hereinafter 10 claimed, as there are other combinations of them, with the several parts somewhat differently arranged, on which I am about to make application for Letters Patent.

15 What I claim as new and of my invention is—

1. In combination with the cartridge-carrier C, provided with the cartridge-chamber c^2 , spring-stop o , placed at the delivery end 20 thereof, and with slot c^4 , suitable mechanism for raising and lowering the said carrier, and the magazine and barrel of the arm placed in the path traversed by said carrier, substantially as described.
- 25 2. In combination with the cartridge-carrier C, provided with the cartridge-chamber c^2 , the spring-stop o , placed at the delivery end thereof, and with slot c^4 , having one or 30 more lips, c^6 , suitable mechanism for raising and lowering the said carrier, and the magazine and barrel of the arm placed in the path

traversed by said carrier, substantially as described.

3. In combination with the cartridge-carrier C, provided with the cartridge-chamber c^2 35 and slot c^4 , suitable mechanism for raising and lowering said carrier, the tongue u , fitting and sliding in said slot, and the barrel and magazine-passage m , placed in the path traversed by said carrier, substantially as de- 40 scribed.

4. In the cartridge-carrier C, the combination of the cartridge-chamber c^2 with the elastic stop o , placed in the delivery end of said chamber, and provided with a flat outer face 45 and a beveled face within the chamber, adapted to cause the said stop to yield and allow the cartridge to be forced outward from the chamber past it, substantially as described.

5. In the cartridge-carrier C, the combination, with the two holes v^2 v^2 through its side wall, of the plunger v^3 , projecting into chamber c^2 , through either one of said holes, across the path of the cartridge, and the spring v , having each member of its bifurcated end 50 adapted to be brought across one of said holes and press upon the said plunger, substantially as described.
